(57) **CLAIM**

We claim the ornamental design for an air pump cart, as shown and described.

DESCRIPTION

FIG. 1 is a front perspective view showing our new design; FIG. 2 is a front view thereof; FIG. 3 is a rear view thereof; FIG. 4 is a left side view thereof; FIG. 5 is a right side view thereof; FIG. 6 is a top view thereof; and, FIG. 7 is a bottom view thereof.

The equal length broken lines in the figures show portions of the air pump cart, which form no part of the claimed design. The dash-dot broken lines define bounds of the claimed design and form no part of the claimed design.
